STITCH-FORMING MECHANISM FOR
SEWING MACHINES

Alfred Grieb, Elizabeth, N. J., assignor to The
Singer Manufacturing Company, Elizabeth,
N. J., a corporation of New Jersey

Application November 28, 1933, Serial No. 700,039

3 Claims. (Cl. 112—181)

This invention relates to improvements in lock-stitch sewing machines and more particularly to improvements in sewing machine loop-taker and thread-case combinations designed to cast loops of needle-thread about an interlocking thread housed within the thread-case.

The primary object of the present invention is to insure the formation of perfect lock-stitches, i. e., stitches in which the needle-thread spirals continuously in the same direction about an interlocking thread, by a sewing machine having a loop-taker journaled for rotation about an axis substantially parallel to the direction of feed. A further object of the invention is to provide for pulling off short lengths of the interlocking thread by means of a pull-off member carried by a loop-taker, without incurring any liability of breakage of the interlocking thread should the loop-taker be inadvertently turned in a retrograde direction, as may occur for instance when the sewing machine is treadle-operated.

With these and other objects of the invention in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the accompanying drawing, Fig. 1 is a front elevation of the improved horizontal-axis rotary loop-taker in a position thereof wherein the pull-off flange at the tail of the hook begins to pull off the interlocking thread. Fig. 2 is a side elevation and Fig. 3 a top plan of the loop-taker in a position wherein the tail of the loop-taker has just passed the portion of the interlocking thread leading to the throat-plate needle-aperture.

Referring to the drawing, the present improvements have been embodied in a sewing machine constructed substantially as disclosed in a U. S. patent application of George M. Eames, Serial No. 691,938, filed Oct. 3, 1933. The sewing machine has a vertically reciprocatory and laterally vibratory needle 1, and the machine may be employed for making either zigzag or straightaway stitch seams. The work is supported by a throat-plate 2 provided with the usual feed-slots 3 for a work-advancing feed-dog 4, said throat-plate also having a needle-aperture 5 which, in the present case, is elongated transversely of the line of feed to accommodate lateral vibrations of the needle 1.

Cooperating with the needle 1, in the formation

of lock-stitches, is a rotary loop-taker 6 disposed below the throat-plate 2 and preferably of the rotary hook type. The loop-taker 6 is carried by a horizontally disposed loop-taker shaft 7 having its axis disposed substantially in a vertical plane containing the line of feed of the work and the needle-path of reciprocation, said loop-taker having a cup-shaped body provided at the outer edge of its periphery with a needle-thread loop seizing beak 8 and a loop-discharging tail or spur 9 adjacent and directed oppositely to the beak 8. Opposite to the beak 8, the peripheral edge of the loop-taker curves outwardly to form an interlocking-thread pull-off member or flange 10 provided with a needle clearance slot 11. The outwardly flaring or thread pull-off edge of the flange 10 merges into an inwardly curving or interlocking-thread-releasing free end 12 which is disposed substantially diametrically opposite to the beak 8, but at the side of the needle-path opposite to the path of said beak 8.

Journaled in the loop-taker 6 is a thread-case which is preferably made in separable sections comprising a holder-section 13 and a cap-section 14 which are secured together by a latch 15 and confine therebetween an interlocking-thread bobbin 16. Suitably secured upon the periphery of the cap-section 14 is a tension-spring 17 for the interlocking thread *b* which then passes to an open thread-delivery eye 18 provided in the outer face of the cap-section 14 by suitably slotting said outer face. According to the present improvement, the thread-delivery eye 18 is located at one side of a vertical plane containing the axis of rotation of the loop-taker and at the side of said plane at which the loop-taker begins to cast a loop of needle-thread *a* about the thread-case. Accordingly, the interlocking thread *b* passes to the throat-plate needle-aperture 5 at an inclination to and from one side of the needle-path of reciprocation. The described location of the thread-delivery eye 18 therefore insures that the needle will uniformly descend at the same side of the interlocking thread *b* in the production of straightaway-stitch seams, thereby obviating the formation of imperfect or so-called "hitch-stitches" in a forward feed of the work.

The thread-case is restrained against rotation with the loop-taker by providing the holder-section 13 at the upper portion of its outer face with a stop-notch 19 entered by a stationary stop-finger 20 secured to the machine frame in any suitable manner (not shown). According to the present improvement, the stop-notch 19 is also disposed at one side of a vertical plane containing

- the axis of rotation of the loop-taker 6, but at 5 the side of said plane opposite to the thread-delivery eye 18. By this disposition of the stop-notch 19, it is so far removed from the length of the interlocking thread *b* between the thread-eye 18 and the throat-plate needle-aperture 5 as to entirely obviate any liability that the thread *b* will be wiped into said stop-notch by the loop of needle-thread *a* cast about the thread-case by 10 the loop-taker, thus insuring the desired lead of the interlocking thread *b* from one side of the needle-path.
- A further advantage residing in the described 15 location of the stop-notch 19 is that thereby the portion 13' of the thread-case holder-section 13 at one side of the stop-notch 19 extends axially outwardly beyond the path of the free end 12 of the pull-off flange 10, said thread-case portion 13' thereby serving to hold the thread *b* outwardly 20 sufficiently far to clear the end 12 of the pull-off flange and obviating any liability that the interlocking thread will be caught and broken by the flange end 12 in any retrograde rotation of the 25 loop-taker.
- Having thus set forth the nature of the invention, what I claim herein is:—

1. In a sewing machine, in combination, a vertically reciprocatory needle, a throat-plate having a needle-aperture, a work-advancing feed-dog, 30 a rotary loop-taker having its axis of rotation substantially parallel to the line of feed, a thread-case for an interlocking thread disposed within said loop-taker and provided with a stop-notch 35 at one side of a vertical plane containing the line of feed and the needle-path of reciprocation, said thread-case having a thread-delivery eye at the opposite side of said plane for directing the interlocking thread over the outer face of the thread-case at one side of said stop-notch to the throat-plate needle-aperture, a stationary stop-finger 40 entering the stop-notch of said thread-case, and a pull-off member carried by said loop-taker to

engage and pull off short lengths of said interlocking thread.

2. In a sewing machine, in combination, a vertically reciprocatory needle, a throat-plate having a needle-aperture, a work-advancing feed-dog, a rotary loop-taker having a needle-thread loop-seizing beak and an interlocking thread pull-off member terminating in a free end substantially diametrically opposite to said loop-seizing beak, a thread-case for an interlocking thread 10 disposed within said loop-taker and provided in the loop cast-off side of its outer face with a stop-notch, said thread-case having a thread-delivery eye at the loop cast-on side thereof for directing the interlocking thread over the outer 15 face of the thread-case at one side of said stop-notch to the throat-plate needle-aperture, and a stationary stop-finger entering the stop-notch of said thread-case.

3. In a sewing machine, in combination, a vertically reciprocatory needle, a throat-plate having a needle-aperture, a work-advancing feed-dog, a rotary loop-taker having a needle-thread loop-seizing beak and an interlocking-thread pull-off flange terminating in a free end at the 20 side of the needle-path of reciprocation opposite to the path of the loop-taker beak, said loop-taker having its axis of rotation substantially parallel to the line of feed, a thread-case for an interlocking thread disposed within said loop-taker and provided with a stop-notch at one side 30 of a vertical plane containing the line of feed and the needle-path of reciprocation, the outer face of said thread-case adjacent to said stop-notch extending axially outwardly beyond the path of 35 the free end of said flange, said thread-case having a thread-delivery eye at the opposite side of said plane for directing the interlocking thread over the outwardly extending portion of the thread-case to the throat-plate needle-aperture, 40 and a stationary stop-finger entering the stop-notch of said thread-case.

ALFRED GRIEB.
